[57] CLAIM

The mini-rigid ureteroscope, as shown and described.

DESCRIPTION

FIG. 1 is a top perspective view of a mini-rigid ureteroscope showing my new design;

FIG. 2 is a bottom perspective view of a mini-rigid ureteroscope or the like showing my new design;

FIG. 3 is a top plan view with the tube broken away for ease of illustration;

FIG. 4 is a front elevational view thereof;

FIG. 5 is a bottom plan view thereof;

FIG. 6 is a left side elevational view thereof;

FIG. 7 is a right side elevational view thereof; and,

FIG. 8 is a rear elevational view thereof.
